UNITED STATES PATENT OFFICE.

DAVID F. COGHLAN AND THOMAS H. SEARS, OF HOLYOKE, MASSACHUSETTS.

STEAM-BOILER.

SPECIFICATION forming part of Letters Patent No. 350,912, dated October 19, 1886.

Application filed October 3, 1885. Serial No. 178,897. (No model.)

To all whom it may concern:

Be it known that we, DAVID F. COGHLAN and THOMAS H. SEARS, citizens of the United States, residing at Holyoke, in the county of 5 Hampden and State of Massachusetts, have invented certain new and useful Improvements in Steam-Boilers, of which the following is a specification, reference being had to the accompanying drawings, forming a part thereof.

10 Our invention relates to improvements in water-tube steam-boilers, or combined cylindrical and water tube boilers; and the objects of our improvements are, first, to increase the heating-surface; second, to bring the products 15 of combustion more directly and continuously in contact with the heating-surface; third, to bring the water into more direct contact with the heating-surface; fourth, to produce a better circulation of the water, and, fifth, to prevent 20 the deposit of sediment in the tubes. We attain these objects by the mechanism illustrated in the accompanying drawings, in which—

Figure 1 is a front elevation of the boiler; 25 Fig. 2, a sectional side elevation; Fig. 3, a rear elevation of a portion thereof, and Fig. 4 an enlarged view of certain parts shown in Fig. 2.

Similar letters refer to like parts throughout 30 the several views.

A is a cylindrical boiler, with the water-legs B and C supporting it upon a suitable setting. B and C communicate with the space in the cylinder, as shown, and are also connected 35 with each other by a series of tubes, D D, &c. Passing through said tubes D D, &c., respectively, are the tubes E E, &c., which extend entirely through the water-legs B and C. By this arrangement there is an annular space 40 for water within the tubes D and surrounding the tubes E. There is also a fire-space within the tubes E and around the tubes D, thus forming a "central-fire-tube water-tube boiler." Below the tubes and at front end is an ash-pit, 45 F, grate G, and combustion-chamber H. The bridge-wall K at the back of the combustion-chamber is carried up to the tubes, and above it is a bridge-plate, L, of suitable material. The bridge-plate L extends the entire width 50 of the combustion-chamber and to the height

of the top of the tubes. The plate L has suitable holes for the tubes D to pass through, but fits with sufficient closeness to prevent the direct passage of the flame over the bridge-wall, thus causing it to pass upward around the 55 tubes to the top of the plate, there striking the boiler-shell A, and the furnace being surrounded by suitable masonry, (not shown in the drawings,) the flame then passes down around the tubes beyond the bridge-wall into 60 the rear end of the central fire-tubes, E E, &c., and thence out at the front end of said tubes into a suitable uptake or smoke-flue. The arrangement described effectually secures the object of bringing the products of combustion 65 into direct and continuous contact with the heating-surface. Large heating-surface is secured and the water brought into close contact with it by the two sets of tubes described. The water fills a space in the form of a thin cylinder heated without and within. To improve 70 the circulation and prevent the deposit of sediment, the tubes are placed in an inclined position, as shown, rather than horizontal. By the use of the central fire-tube there is a narrowing of the space from a cylinder to a cylindrical shell in the water-tube, thus increasing 75 the force of the current and sweeping all sediment out.

The form of the rear water-leg, C, is shown 80 in Fig. 3. A foot, c, upon each side, forming a part of the water-space, serves as a support and leaves a central passage for the flame and gases. The front end, B, is of similar construction. The water in the boiler entirely 85 fills the water-tube space and partially fills the cylindrical boiler A above, leaving the necessary steam-space. Suitable openings or nozzles for steam-outlet are provided at a a, and a man-hole at b.

The arrangement of the central fire-tubes, E, and water-tubes D is shown on a larger scale in Fig. 4.

Having fully described our invention, what we desire to claim and secure by Letters Patent is—

In a steam-boiler, the combination, with the cylindrical boiler or drum A, provided with front and rear water-legs, B and C, communicating therewith, the rear leg, C, having feet 100

c, which communicate with said legs, between which is a central passage for the products of combustion, of the inclined tubes D, opening into said water-legs, the inclined tubes E, arranged centrally in the said tubes D, and passing entirely through the said water-legs, and the central bridge-plate, L, for diverting the

products of combustion upward, substantially as set forth.

DAVID F. COGHLAN.
THOMAS H. SEARS.
